GEAR SHIFT HANDLE FOR AUTOMOBILES

Edwin E. Lohn, 231 S. Peck Drive, Beverly Hills, Calif.

Filed Feb. 21, 1962, Ser. No. 68,919

Term of patent 14 years

(Cl. D14—6)

FIG. 1.

FIG. 2.

FIG. 3.

FIGURE 1 is a side elevational view of a gear shift handle for automobiles showing my new design;

FIGURE 2 is a front elevational view thereof; and

FIGURE 3 is a top plan view thereof.

The portion shown in broken lines is included for illustrative purposes only.

I claim:

The ornamental design for a gear shift handle for automobiles, substantially as shown and described.
